Fig. 5

Fig. 6

Fig. 7

FIG. 1 is a front elevation of a telephone subset showing my new design;

FIG. 2 is a top plan view thereof;

FIG. 3 is a left side elevation thereof;

FIG. 4 is a left side elevation mounted in an alternate position;

FIG. 5 is a rear elevation of the telephone subset;

FIG. 6 is a front perspective view thereof; and

FIG. 7 is a rear perspective thereof.

I claim:

The ornamental design for a telephone subset, substantially as shown and described.
